DESIGN FOR A HANDLE BAR

Harry H. Henry, Chicago, Ill., assignor to Battery
Patents Corporation, Chicago, Ill., a corpora-
tion of Illinois

Application September 19, 1936, Serial No. 64,929

Term of patent 14 years

To all whom it may concern:

Be it known that I, Harry H. Henry, a citizen
of the United States, residing at Chicago, county
of Cook and State of Illinois, have invented a new,
original, and ornamental Design for a Handle Bar,
of which the following is a specification, refer-
ence being had to the accompanying drawing,
forming a part thereof, in which:

Figure 1 is a plan view of a bicycle handle bar,

showing my new design; Fig. 2, a sectional view,
the section being taken as indicated at line 2 of
Fig. 1; and Fig. 3, a sectional view, the section
being taken as indicated at line 3 of Fig. 1.

I claim:

The ornamental design for a handle bar, as
shown.

HARRY H. HENRY.
